UNITED STATES PATENT OFFICE

108,290

DESIGN FOR A SWEATER

Charles Levine, New York, N. Y.

Application January 13, 1938, Serial No. 74,259

Term of patent 3½ years

To all whom it may concern:

Be it known that I, Charles Levine, a citizen of the United States of America, residing in the city of New York, county of New York, and State of New York, have invented a new, original, and ornamental Design for a Sweater, of which the following is a specification, reference being had to the accompanying drawing, forming part thereof.

Fig. 1 is a front view of a sweater showing my new design.

Fig. 2 is a rear view thereof.

The characteristic feature of my design resides in lacey vertical inserts on the front and rear portion of the sweater as shown.

I claim:

The ornamental design for a sweater, substantially as shown and described.

CHARLES LEVINE.
